UNITED STATES PATENT OFFICE.

JOHN SHAFFER, OF LOGANSPORT, INDIANA.

HAY-RACK.

SPECIFICATION forming part of Letters Patent No. 257,770, dated May 9, 1882.

Application filed November 16, 1881. (No model.)

To all whom it may concern:

Be it known that I, JOHN SHAFFER, of Logansport, in the county of Cass and State of Indiana, have invented a new and Improved Hay-Rack and Wagon-Box; and I do hereby declare that the following is a full, clear, and exact description of the same, reference being had to the accompanying drawings, forming part of this specification, in which—

10 Figure 1 is a perspective view of my improved wagon-box and hay-rack. Fig. 2 is a side elevation of one of the sides of my wagon-box. Fig. 3 is a side elevation of one of the end braces of the hay-rack. Fig. 4 is a side elevation of one of the intermediate braces of the hay-rack. Fig. 5 is a view of a hay-ladder. Figs. 6 and 7 are views of modified forms of end and middle metallic braces. Fig. 8 is a front view of an end-gate of the wagon-box, 20 and Fig. 9 is a top view of a cross-bar of the wagon-box.

Similar letters indicate corresponding parts in all the figures.

My invention relates to improvements in hay-racks and wagon-boxes; and it consists in the peculiar construction and arrangement of the parts, as hereinafter more fully set forth.

In the accompanying drawings, *a a* represent the side-boards of my improved wagon-box, 30 similarly constructed, so that a description of one will suffice for both. Each side-board *a* is provided with a horizontal row of mortises, *c c*, made near the lower edge of the side-board *a*, and adapted, excepting the end ones, to receive the cross-bars *h* inserted therein.

35 *e e* are hooks rigidly secured to the outer faces of the side-boards *a*, their hooked ends projecting slightly below the side-boards and carrying the ends of the cross-bars *d d*, thus leaving a space between the upper faces of the cross-bars *d* and the lower faces of the cross-bars *h* for the boards constituting the bed or bottom of the wagon-box. The outer boards, *i i*, of the bed or bottom of the wagon are beveled in the same direction along their inner faces, or are wedge-shaped, and the central board, *k*, has its edges beveled in a contrary direction, so as to form a wedge-shaped piece adapted to slide into the wedge-shaped opening formed between the inner edges of the boards *i i*, and thus form a tight wagon-bed to prevent the egress of seed or other matters.

l represents a pin, by means of which the wedge-shaped central bottom board, *k*, is held in place between the other boards. By this 55 construction the bottom of the wagon can readily be removed to discharge a load at once without the labor of unloading it.

The upper horizontal row of mortises, *b b*, (see Figs. 1 and 2,) are formed for the insertion of the tenons *m' m'* of the end braces, *m*, and the tenons *n' n'* of the intermediate braces, *n n*, to which the slats *o o* are secured, forming the hay-rack. The tenons *m' m'* on the end braces, *m*, are made longer than the tenons *n' n'* on the 65 intermediate braces, *n*, so as to extend through the side-boards *a* of the wagon-box, and thence into the recesses *p* of the end-gates, the end braces, *m*, and the end-gates *r* being securely attached to each other and the wagon-box by 70 the removable rods *q* passing through holes in the projections *t t* in the end-gates and through holes in the tenons *m' m'* of the braces. The projections *s s* at the lower ends of the end-gates project through the end mortises of the lower 75 row of mortises, *c*, and the end braces rest upon them. The tenons *n' n'* of the intermediate braces, *n*, pass through the intermediate mortises, *b b*, and the lower ends of the intermediate braces, *n*, rest on the ends of the cross-bars *h*, and are held in place by the pins *u* passing through holes near the ends of the cross-bars *h*.

v represents a hay-ladder pivoted in the sides *a*. By this construction it will be seen 85 that the sides of the hay-rack can be separated from the wagon-box, and the sides, end-gates, hay-ladder, cross-bars, and bottom or bed of the box separated and packed away for safe keeping or transportation, and readily put 90 together without employing a skilled workman.

The braces shown in Figs. 6 and 7 are a modified form of metallic braces, Fig. 6 showing the end brace, and Fig. 7 an intermediate brace, made of sheet metal, the angular flange 95 *w* of Fig. 7 fitting over the upper edge of the side-board of the wagon.

What I claim, and desire to secure by Letters Patent, is—

1. The combination, with the end-gate *r*, provided with the projections *t t* and recesses *p*, and side-board *a*, provided with end mortises, *c*, of the end brace, *m*, provided with a tenon, *m' m'*, extending through the side-board and into

the recess, and secured thereto by a pin, *q*, substantially as described, and for the purpose set forth.

2. The combination of the side-boards *a*, provided with the mortises *b c* and hooks *e*, removable cross-bars *h d*, removable wedge-shaped boards *i i k*, braces *m m' n n'*, connected by slats *o o*, end-gates *r r*, constructed

as set forth, and pins *l q u*, whereby the hay-racks and wagon-box can be separated or put together, substantially as described, and for the purpose set forth.

JOHN SHAFER.

Attest:

Q. A. MYERS,
GEORGE T. WEBSTER.
